UNITED STATES PATENT OFFICE.

MAX KELTING, OF BOCHUM, GERMANY.

COKE OVEN.

Application filed July 13, 1925, Serial No. 43,428, and in Germany July 18, 1924.

My invention relates to coke ovens and more especially to the heating flues forming part of such ovens. It is an object of my invention to promote the gravity circulation 5 of the heating gases by means of the fresh gas and air for combustion which are supplied to the flues through the usual burners.

To this end I so arrange the said burners and the passages for discharging a certain 10 percentage of the circulating gases that the direction in which the burners deliver and the waste gases are discharged from the passages, conform to the direction in which the gases flow at the points of delivery and discharge. 15

In a preferred embodiment of my invention I provide a main flue and transverse partitions therein which do not extend as far as the bottom and the top of the main 20 flue. By these means I obtain a plurality of parallel and preferably vertical uptakes and downtakes in connection with the main flue, and in these uptakes and downtakes I obtain closed circuits of flowing gases. Gas 25 and air for combustion are continuously introduced into these circuits at a suitable point by burners, and a corresponding percentage of waste gases is discharged therefrom at another point of the circuit.

30 Preferably the gas and air for combustion are introduced into the uptakes so that the buoyancy of the burning mixture causes it to rise therein. This tendency may be promoted by introducing the gas and air in parallel with the axis of the uptakes, that is as a rule vertically upwards, and by injecting the gas and air through a nozzle.

In heating flues and particularly in long vertical flues a considerable temperature 40 gradient occurs if gas and air are introduced at one point of the flue and the waste gases are discharged at another point. It has already been proposed to make such a flame longer and more uniform by admixing inert 45 gas for instance smoke gas.

According to my invention no inert gas is admixed and the percentage of inert gas which is contained in the products of combustion remains with the circulating gas with 50 the exception of an amount corresponding to the percentage of fresh gas and air introduced which amount is continuously discharged.

It has also been proposed to introduce gas 55 and air in parallel streams into the heating

flues through vertical nozzles in order to increase the length of the flame. The effect obtained is due to the parallel flow of gas and air by which the mixing of the fluids is delayed. 60

According to my invention, the kinetic energy of the flowing fluids under pressure is utilized for promoting the circulation.

It has also been proposed to effect continuous circulation in the heating flues of a 65 coke oven by introducing the air for combustion in an upwardly directed stream into the circulating gases and by introducing the gas in a downwardly directed stream at the point where the upward flow is reversed. 70 This method, however, failed to operate because the action of the rising stream of air which in any case would not be sufficient for obtaining the desired result, was directly counteracted by the buoyancy of the gas. 75 Moreover introducing gas at the point where the direction of the gas is reversed renders its energy ineffective.

In the drawings affixed to this specification and forming part thereof a coke oven 80 embodying my invention is illustrated diagrammatically by way of example. In the drawings:

Fig. 1 is a longitudinal vertical section of a series of flues, and 85

Fig. 2 is a transverse vertical section of an experimental flue and burner.

Referring now to the drawings: 1 and 2 are horizontal walls of the coke oven defining a horizontal heating flue 3. Uptakes 90 and downtakes *a* and *b*, respectively are formed in said flue by transverse partitions 4. The partitions do not extend as far as the top and bottom of the flue 3 so that each of the uptakes and downtakes are connected 95 by a passage *c* at the top and a passage *d* at the bottom. Burners 5 comprising an air nozzle *g* and a gas pipe *f* are arranged in the wall 2 below each uptake *a*, and discharge ports *h* are arranged below each 100 downtime *b*.

The products of combustion of each burner 5 rise in the uptakes *a* and are deflected into the downtakes *b* at the top of the partitions

4. A percentage of the gases which correspond to the percentage of fresh gas and air for combustion supplied through the burners 5 is discharged through each port *h* below the downtakes. The remainder of the gases is deflected into the adjoining uptakes *a* 110

through the passage *d* and partakes in the continuous circulation of the gases as indicated by the arrows. The ports *h* are connected to a common main flue, not shown.

5 It will be understood that the temperature of the gases is considerably higher in the uptakes *a* than in the downtakes *b* and that the specific gravity of the gases is correspondingly less in the uptakes than in the 10 downtakes. This effects an automatic gravity circulation as indicated. As soon as the circulation has been started, the gases will circulate continuously and the fluids from the burners have no tendency to short-circuit 15 into the discharge ports *h* through the passage *d*.

The energy of the circulation may be increased by injecting the fluids from the burner under any desired pressure.

20 It is customary in coke ovens to introduce gas from below to the vertical gas flues but in my invention a much better effect is achieved by the continuous circulation of the gases. On the other hand, the circulation 25 of the gases only becomes really effective when the buoyancy of the products of combustion is utilized for promoting the circulation.

This theory has been confirmed by experiments 30 in an experimental oven which is illustrated in Fig. 2. In this figure 6 is the oven and 7 is the single partition subdividing the oven chamber into an uptake 8 and a downtime 9 which are connected by short 35 horizontal passages at the top and the bottom, as in the flue 3 Fig. 1.

Gas and air were introduced through the burner *m*, the gas pipe being indicated at *f'*. *h'* is the discharge port. When the gas 40 was ignited at the burner *m* the desired circulation started immediately. As soon as the operation had been properly started, the gas supply was shut off and the temperature at the top and the bottom of the oven was 45 measured by means of an optical pyrometer. The temperature was 1060 degrees centi-

grade at the bottom and 1010 degrees centigrade at the top corresponding to a temperature gradient of only 50 degrees for a total length of flue equal to 2.5 metres.

50

I wish it to be understood that I do not desire to be limited to the exact details shown and described, for obvious modifications will occur to a person skilled in the art.

55

I claim:—

1. Heating chamber for coke ovens having an uptake conduit and a downtime conduit connected together at their top and bottom ends respectively, a burner with an air nozzle at the lower end of said uptake conduit and communicating therewith, and means for discharging part of the products of combustion from said heating chamber at the lower end of said downtime conduit.

60

2. Heating chamber for coke ovens having an uptake conduit and a downtime conduit connected together at their top and bottom ends respectively, a burner with an air nozzle at the lower end of said uptake conduit and communicating therewith, and a vertical discharge duct at the lower end of said downtime conduit adapted for discharging products of combustion from said heating chamber.

75

3. Heating chamber for coke ovens having an uptake conduit and a downtime conduit connected together at their top and bottom ends respectively, a burner with an air nozzle at the lower end of said uptake conduit and communicating therewith, and means for discharging part of the products of combustion from said heating chamber at the lower end of said downtime conduit, said burner being adapted to discharge gas into 80 said uptake in a direction along the same, and said means comprising a duct extending in the same direction as said downtime conduit.

85

In testimony whereof I affix my signature.

MAX KELTING.
